CHOPPER FOR NUTS OR THE LIKE

Efrem M. Ostrowsky, Highland Park, Ill., assignor to Nibot Corporation, Chicago, Ill., a corporation of Illinois

Filed Jan. 16, 1963, Ser. No. 73,200

Term of patent 14 years

(Cl. D89—1)

FIG. 1

FIG. 3

FIG. 1 is a top plan view of a chopper for nuts or the like, embodying my new design;

FIG. 2 is a front view; and

FIG. 3 is a side view of the chopper as seen from the right-hand side of FIG. 2.

I claim:

The ornamental design for a chopper for nuts or the like, substantially as shown.
